UNITED STATES PATENT OFFICE.

ALBERT CARO, OF MAYWOOD, AND ABE BERLINER, OF CHICAGO, ILLINOIS, ASSIGNEES
TO CARO-BERLINER RADIATOR CORPORATION, A CORPORATION OF ILLINOIS.

RADIATOR FOR AUTOMOBILES.

1,209,810.

Specification of Letters Patent. Patented Dec. 26, 1916.

Application filed April 5, 1915. Serial No. 19,300.

To all whom it may concern:

Be it known that we, ALBERT CARO, of Maywood, Cook county, Illinois, and ABE BERLINER, of Chicago, Cook county, Illinois, both subjects of the Czar of Russia, have invented certain new and useful Improvements in Radiators for Automobiles; and we do hereby declare the following to be a full, clear, and exact description of the invention, such as will enable others skilled in the art to which it appertains to make and use the same.

This invention relates to improvements in radiators for automobiles or similar motor-propelled vehicles for any connection with water cooled devices in which it is desirable to radiate the heat absorbed by the water in performing its cooling function.

The invention relates, however, particularly to radiators for automobiles and is designed and adapted for such use.

The object of the invention is to provide a radiator equipped with a multiplicity of radiating units, each having a relatively large radiating surface compared to the cubic contents thereof and in which each radiating unit may be easily removed and replaced for purposes of repair and in which, furthermore, a broken unit may be removed and the openings, through which the same communicates with the body portions of the radiators, plugged to prevent leakage pending the insertion of a new or repaired unit in its place.

A further object of the invention is to provide a radiator having removable radiating units which is otherwise so constructed and arranged as to enable it to be easily assembled and taken apart for purposes of repair and which is further so constructed and arranged as to provide a freer circulation of air around the radiator units in a greater number of directions than is possible with the radiators now generally employed for the same purpose.

Another object of the invention is to provide a radiator so constructed and arranged as to enable the circulation of air around the radiator units thereof to be easily and quickly increased and decreased according to the season, or severe changes of weather, to prevent the freezing of water in the radiator units and consequent injury thereto.

In the accompanying drawings illustrating a suitable embodiment of the invention: 55 Figure —1— is a view in front elevation, partly in vertical transverse section, of a radiator constructed in accordance with our invention. Fig. —2— is a vertical longitudinal section of the same on the line 2—2 of 60 Fig. —1—. Fig. —3— is a fragmentary detail central vertical section showing the method of connecting the radiator units with the body portions of the radiator. Fig. —4— is a view similar to Fig. —2— 65 showing how the circulation of air around the radiator units may be materially decreased when desired. Fig. —5— is a detail horizontal section on the line 5—5 of Fig. —1—. 70

The radiator comprises a base member 1 and cap member 2, each of which is adapted to contain a relatively large quantity of water or other liquid adapted to absorb heat generated by the motor with which said 75 parts are adapted to be connected by means of the pipes 3 and 4 shown in Fig. —2—. The liquid is introduced through the opening normally maintained closed by means of the plug 5. The said body portions 1 and 80 2 are provided contiguous to their ends with flanges 6 and 7, which are adapted to be bolted to similar or companion flanges 8 and 9 on the standards 10, and adapted to connect said body portions 1 and 2 firmly with 85 each other and maintain them the requisite distance apart. The said standards 10 are skeleton structures which may be made of sheet metal or cast, the front and rear portions thereof presenting unbroken walls, the 90 side walls thereof being provided with large openings for the passage of air to the radiator units interposed between said standards and between the portions 1 and 2 of the radiator. Mounted in these standards are 95 foraminous protecting members 11 for preventing contact of the finger with the radiator units 12. Each of said radiator units 12 consists of a helically coiled pipe of relatively small diameter and having its end 100 portions axially disposed relatively to the intermediate helically coiled portions, as clearly shown in Fig. 3. To one end of each pipe there is secured the member 13 of a union or similar coupling which is adapted 105 to be connected to its companion member 14

rigidly mounted upon one of the opposed horizontal walls of the body portions 1 and 2 of the radiator respectively. The other end of each pipe is threaded for connection with a bushing or flange 14^a mounted in or upon the other of the said opposed horizontal walls. The threaded members of the unions are preferably mounted upon a wall of the body portion of the radiator so that 10 in the event of the removal of one of said units for purposes of repair, the said threaded member of said union thus opened may be closed by means of a suitable cap fitting the same, to be carried in the automobile, 15 and the companion flange or bushing 14^a may be closed by a suitable plug. These caps and plugs are omitted from illustration as being readily understood by persons skilled in the art. A jam nut 14^b on the 20 threaded member of each union prevents accidental loosening and leakage in a well-known manner.

It will be observed that in our radiator all of the water passing to the motor, must 25 during circulation, pass through the said radiator units 12 where it is exposed to the absorption of its heat by the air circulating around said units in a well-known manner. The standards 10 are not adapted to contain 30 water or constitute ducts for the passage of water from the upper member 2 to the lower member 1 of the radiator, it being well known that water in circulation will take the path of least resistance and in all cases 35 where the parts corresponding to the standards 10 of our structure are hollow and adapted to permit the passage of water in circulation, the water passes through these parts to the substantial exclusion of its passage 40 through those parts of the radiator corresponding to the radiator units of our structure, thus preventing such a complete absorption of heat from the water as will prevent the same from attaining a temperature 45 equal or exceeding the boiling point. The said radiator units are protected against injury by means of the foraminous plates 15 mounted upon the front and rear portions of the structure and abutting 50 against portions of the walls of the body portions 1 and 2 and against flanges 16 of the standards 10 and which are securely held in place by means of the bolts 17 passing through openings in the corners of said plates 15 and through the space containing 55 the radiator units. By removing the nuts from said bolts, the said plates or either of them, may be easily removed or replaced.

In excessively cold weather during which 60 there is danger that the liquid contained in the radiator may freeze, it is desirable to cut down the circulation of air around the radiator units. In our structure, this may be easily accomplished by removing the 65 front plate 15, inserting a sheet 18 of insin-

glass or other suitable material between the same and the parts against which said plate abuts and then replacing said plate and securing the same. This will prevent the rush of air through the radiator and will obviously greatly reduce the circulation of air and radiation of heat. 70

Our device is very efficient, durable and cheap and is, as will be obvious, easily and quickly repaired. 75

We claim as our invention:—

1. A radiator comprising an upper and a lower reservoir for liquid, connection to the upper reservoir for receiving heated liquid from a liquid heating element such as a hydro-carbon motor, connection to the lower reservoir for returning cooled liquid to the heating element, and a plurality of radiating units connecting the two reservoirs and through which the liquid flows from the upper reservoir to the lower reservoir, said units constituting the only passages through which the liquid can flow from the upper to the lower reservoir standards rigidly supporting the upper reservoir above the lower reservoir, large free air inlet openings in said standards and inwardly curved foraminous plates preventing free access to said units through said standards. 80

2. A radiator comprising two reservoirs for liquid connected to discharge into and receive liquid from a liquid heating element such as a hydro-carbon motor, standards supporting one of said reservoirs at an elevation above and upon the other, the opposing walls of said reservoirs and the opposed standards bordering a rectangular space, and a plurality of radiator units disposed in said space and detachably connected at opposite ends with said reservoirs and foraminous plates removably mounted between said standards and said reservoirs for inclosing the said space containing said radiator units and a plate adapted to be disposed between one of said foraminous plates and the parts 105 against which the same is adapted to abut for preventing free passage of air for circulation around said units. 110

3. A radiator comprising two reservoirs for liquid connected to discharge into and receive liquid from a liquid heating element such as a hydro-carbon motor, skeleton standards supporting one of said reservoirs at an elevation above and upon the other, the opposing walls of said reservoirs and the opposed standards bordering a rectangular space, and a plurality of radiator units disposed in said space and detachably connected at opposite ends with said reservoirs, said standards permitting free passage of air to said space from either side of the same and foraminous plates removably mounted between said standards and said reservoirs for inclosing the said space containing said radiator units and a plate 115 120 125 130

adapted to be disposed between one of said plates and the parts against which the same is adapted to abut for preventing free passage of air for circulation around said 5 units and foraminous protectors preventing free access to the radiator units through said standards.

In testimony whereof we have signed our

names in presence of two subscribing witnesses.
